P. T. GODSAL.

SMALL ARM.

APPLICATION FILED JULY 30, 1920.

1,393,112.

Patented Oct. 11, 1921.

Inventor:-
Philip Thomas Godsal
By his Attorney,
Baldwin & Wright

UNITED STATES PATENT OFFICE.

PHILIP THOMAS GODSAL, OF ISCOYD PARK, ENGLAND.

SMALL-ARM.

1,393,112.

Specification of Letters Patent. Patented Oct. 11, 1921.

Application filed July 30, 1920. Serial No. 400,044.

To all whom it may concern:

Be it known that I, PHILIP THOMAS GODSAL, a subject of the King of Great Britain, residing at Iscoyd Park, in Flintshire, near 5 Whitchurch, in the county of Salop, England, have invented new and useful Improvements in Small-Arms, of which the following is a specification.

This invention relates to improvements 10 in the block bolt action described in my British Specification No. 136617.

The object of the present invention is to provide an action wherein the striker and main spring may be readily inserted from 15 the rear of the carrier, may be securely held in position and may be easily withdrawn. A further object of the invention is to provide a simple and efficient form of safety catch.

20 In my former specification I have described an action in which the striker and firing pin are used, but for the purposes of the present specification the invention will be described in connection with a direct acting striker (as in previous actions of my invention and design) although the invention may be adapted to be used with my other actions.

When using the rifle with sporting car- 30 tridges, giving a heavy pressure it may be advisable to use a firing pin.

According to this invention I form a striker of two pieces connected together by a screw, the fore part extending backward 35 from the point to an enlargement or piston and the rear part consisting of a stem screwing into the piston and a cocking piece which latter extends around under the carrier and engages with a sear in the usual 40 manner. A plug which acts both as an abutment for the rear end of the main spring and as a bearing for the stem is fitted in the bore of the carrier and extends rearwardly beyond the carrier. The plug is of the same 45 diameter as the bore of the carrier for the greater part of its length, but is of greater diameter at the rear end. At the front end of the plug is a diaphragm fitting the bore of the carrier and having a hole to receive 50 the stem of the striker and rearwardly from this diaphragm a passage is cut for the striker and the cocking piece to travel in, and near the front end of the plug are two lateral lugs. The bore of the carrier is of 55 the same diameter throughout and along the bottom is cut a straight shallow groove ex-

tending the length of the bore, and on the piston of the striker is a downwardly extending projection which fits into the groove and can travel freely along it. The projection and groove prevent any tendency to turn on the part of the fore part of the striker. A shallow groove is cut around the bore of the carrier near its rear end to receive the lateral lugs on the plug and to enable these lugs to be inserted into this groove before they are turned a longitudinal groove is cut in the top of the bore as far forward as the above mentioned groove and of the same size as the lugs for the upper lug to 70 travel in.

As above mentioned the plug is of the same diameter as the bore of the carrier except for a lug at the rear end which is approximately of the same diameter as the 75 outside of the cylinder of the carrier and is rounded off at the rear end.

I insert a safety catch consisting of a broad ring having a radial thumb piece into the space between the end of the carrier and 80 the lug on the plug. The ring has in it a gap through which the cocking piece can pass when the radial thumb piece is pressed down to the right in which position the rifle can be fired.

If the thumb piece is turned 180° to the left the ring passes between the cocking piece and the stem of the striker and so holds the piece safe.

The rear end of the ring is so formed that 90 as it is turned it engages the inside of the bent part that joins the cocking piece to the stem of the striker, and so draws it back sufficiently to draw the cocking piece from out of engagement with the sear. Thus as 95 long as the thumb piece is turned to the left the rifle cannot be fired.

A spring plunger may be inserted in the thumb piece to take into small recesses in the plug and so to hold the safety catch in 100 the open or closed position.

My invention is illustrated by the accompanying drawing, Figure 1 of which is a right hand view of an action showing the carrier in section; Fig. 2 is a right side view 105 of the striker; Fig. 3 a rear view; and Fig. 4 a front view thereof; Fig. 5 is a section on the line 5—5, Fig. 1; Fig. 6 is a rear view of the carrier; Fig. 7 is a section of the plug; Fig. 8 is a front view thereof; Fig. 110 9 is a side view of the safety catch; Fig. 10 a part sectional rear view thereof; Fig. 11

is a front view showing the safety catch in the safe position; and Fig. 12 is a view showing it in the firing position.

A is the carrier which is bored as shown 5 to receive the striker which consists of two parts, the fore part B, the rear end of which is enlarged to form a piston B¹ fitting in the bore of the carrier A, and the rear part C, the front of which screws into the piston B¹, 10 while the rear extends around under the carrier and forms a cocking piece C¹ which engages a sear D. In the rear of the carrier A fits a plug E which is itself bored to allow the stem of the part C to pass through it. 15 At the front of the plug is a diaphragm E¹ fitting the bore of the carrier. Near the front of the plug are two lugs E² which take 20 into a groove A¹ cut around the bore of the carrier near its rear end and to enable the lugs to reach this groove a longitudinal groove A² is cut in the top of the bore from the rear end thereof as far forward as the groove A¹. Between the diaphragm E¹ and the piston B¹ lies a main spring F. At the 25 rear of the plug is a lug E³. In order to prevent the possibility of the fore part B turning a straight shallow groove A³ is cut along the bottom of the bore to receive a projection B² on the piston B¹. 30 The safety catch consists of a ring of steel G having in it a gap. It is provided with a thumb piece G¹. This catch surrounds the plug just behind the rear of the carrier. When the thumb piece is pressed down to 35 the right and is in the position shown in Fig. 12 the cocking piece C¹ can pass through the gap in the ring and the piece can be fired, but when the thumb piece is turned in the other direction and lies in the position shown in Fig. 11, the ring G lies 40 in the path of that part of C which unites the cocking piece to the stem and therefore the piece is safe. 45 The ring G may be beveled off as seen at G² so that when the catch is turned into the safe position this part bears against the cocking piece and so draws the striker back sufficiently to remove the cocking piece from engagement with the sear. 50 E⁴, E⁴, are two recesses cut in the plug E and adapted to receive the end of a spring plunger G³ carried by the thumb piece G¹

by which the catch is held in the required position.

To assemble the above parts, I first put the 55 safety catch on the plug on which it is retained by the lug E³ and then I push the stem C through the plug as far as it will go. The spring F is then threaded on to the stem which is then screwed into the piston B¹. 60 I then insert the striker with the spring, plug and safety catch thus assembled on it, into the carrier and press the plug home. As the plug is pressed home the cocking piece comes against the end of the carrier and is pressed 65 back by it, and when the lugs E² reach the groove A¹ the plug etc. are given a quarter turn (the screw in the piston allowing this to be done) so that the lugs E² hold the plug in place. The cocking piece on reaching the 70 passage cut for it snaps into its place. Thus the plug is locked in position by the cocking piece and cannot be dismounted before the cocking piece has been forced back clear of the carrier.

Having now particularly described and ascertained the nature of my said invention and in what manner the same is to be performed, I declare that what I claim is:—

1. In a block bolt action, the combination 80 of a carrier, a striker formed in two parts screwed together and working in the carrier and a detachable plug fitting the rear of the carrier and locked therein by the striker.

2. In a block bolt action, the combination 85 of a carrier, a striker formed in two parts screwed together and working in the carrier, a detachable plug fitting the rear of the carrier, a safety catch consisting of a ring surrounding the plug and having a portion cut away to allow the striker to move, and a thumb piece adapted to turn the catch around the plug.

3. In a block bolt action, the combination 95 of a carrier, a striker formed in two parts screwed together and working in the carrier, a detachable plug fitting the rear of the carrier locked therein by the striker, a safety catch consisting of a ring surrounding the plug and having a portion cut away to allow 100 the striker to move, and a thumb piece adapted to turn the catch around the plug.

PHILIP THOMAS GODSAL.
